CLAMPING DEVICE

Elmer H. Brunner, East Cleveland, Ohio, assignor
to Brunner-State Studios, Inc., Cleveland,
Ohio, a corporation of Ohio

Application December 14, 1932
Serial No. 647,135

11 Claims. (Cl. 24—255)

This invention relates to a device for attachment to the margins of strips of material and the like, whereby they may be handled, manipulated for treatment and suspended for drying, exposure or exhibition; more particularly, the device is especially adapted for use in connection with the developing of photographic films.

One object of the invention is to provide a device of this character of improved construction in which danger of chemicals or water lodging in or upon portions of the device or between said device and the sheets or strips clamped and being retained thereby, is materially reduced or substantially eliminated.

Another object of the invention is to provide a device of this character having spaced pairs of gripping arms so arranged and related that the same are guided toward and from each other, whereby the opposed contact elements are maintained in alinement and damage thereto is avoided.

Another object of the invention is to construct a device of this character of improved construction providing but two pairs of gripping members, thereby minimizing danger of weakening or damaging the sheet or strip to which the device is attached.

Another object of the invention is to provide a device of this character having at one end spaced pairs of gripping arms and at its other end spaced loops permitting the device to be readily supported or suspended in a vertical position.

Another object of the invention is to provide a device of this character formed of two sections of resilient wire which are respectively bent and symmetrically arranged to permit free circulation of air through and between the sections and adjacent portions of the sheet or strip to which the device is attached and to permit the attachment of a weight without affecting the operation of the device.

A further object of the invention is to provide a device of this character that is formed of few parts and readily manufactured.

Other objects of the invention will be apparent to those skilled in the art to which my invention relates from the following description taken in connection with the accompanying drawing, wherein

Fig. 1 is a fragmentary perspective view showing the preferred application of the devices embodying my invention.

Fig. 2 is a fragmentary perspective view of the device suspended from a bar D, and also

a dotted line showing of the jaws in open position.

Fig. 3 is a perspective view of the device in inverted position having a weight attached thereto.

Fig. 4 is a front view of the device shown in Figs. 1 and 2.

Fig. 5 is a sectional view of the device on the line 5—5 of Fig. 4.

Fig. 6 is a side view of the weight.

Fig. 7 is an enlarged fragmentary perspective view of the gripping jaws, and Fig. 8 is a sectional view of the weight on the line 8—8 of Fig. 6.

In the drawing, A indicates a sheet or strip of material suspended by a device, indicated as an entirety at 1. Where the sheet or strip is thin or tends to curl or where the sheet or strip is of a character requiring manipulation for any purpose, such as a photographic film, one device 1 is used for suspending the sheet or strip from a support, such as indicated at B and another device 1, preferably having its weight supplemented by a body 2, is attached to the lower end of the sheet or strip. In practice, in developing photographic films A, the support B is provided with a plurality of devices 1, as shown in Fig. 1 and each undeveloped film (after tearing or cutting off the light-proof end strips) is attached at one end to one device and a weight carrying device is attached to the other end of each undeveloped film. The support B is then manipulated manually or by suitable conveying mechanism into the chemical baths, fixing and washing solutions and into or through a drying atmosphere.

In developing film strips the pairs of gripping arms engage the end portions of the strips and gummed strips a which secure the light-proof end strips to the films.

The device 1 comprises two sections 3 of resilient wire of equal length and each section is bent intermediate its ends to form a loop 4 and spaced legs 5, 5a. The terminating end portions of the legs are respectively bent laterally toward the other leg, which lateral portion extends beyond a median plane disposed between the legs, as shown at 7, and the extended portions are then reversely bent or curved, as shown at 8, the free ends of which normally engage each other, due to the resiliency of the wire sections. By reversely bending and curving the end portions of the legs 5, 5a, it will be seen that pressure upon the legs, one toward the other, will cause a separation of the gripping arms 6, 6a, (see dotted lines in Fig. 2) and release of pressure will permit

the arms to automatically grip the strip A. As the legs 5, 5a, are of substantially equal length and similarly bent at their terminating end portions, their free ends or gripping elements are normally disposed in the median plane between the legs.

As shown in Figs. 4 and 5, the bent portions 7 are in different planes transversely of the median plane above referred to and the curved portions 8 are bent laterally to position their gripping elements in alignment. The bent portions are arranged to engage each other when moving relatively, so that in the operation of the arms 6, 6a, away from and toward each other, the gripping elements are guided and maintained in alignment. It will also be noted that the arms 6, 6a, of the pairs of legs 5, 5a, occupy the same relation to the arms 6a, 6a; that is, the former arms may be on the outside or the inside of the latter arms, the latter arrangement being shown. In either of these arrangements, both pairs of arms co-operate to prevent dis-alinement of each pair of gripping elements since corresponding legs cannot readily swing laterally relative to the other pair of legs.

The corresponding legs of the wire sections 3 are shaped and connected together in a manner which maintains the loops and gripping arms in spaced relation and insures movement of adjacent or corresponding legs together. For this purpose the legs 5, 5a, of each section 3 between the loops 4 and bent portions 7 are preferably offset inwardly toward the legs of the other section, as shown at 9, for engagement with and connection to similar offset portions of the latter legs. As shown, each offset 9 on one leg 5 or 5a is connected to the corresponding leg 5 or 5a of the other section so that the pairs of legs 5, 5a, move together. The offsets of adjacent legs are preferably connected by a clip 10 bent there-around, as shown. Each clip 10 is preferably provided with extensions 11, 12, these being enlarged to form press plates, which are engaged by one's fingers to facilitate operation of the gripping arms, in opposition to the resiliency of the wire sections. The plates 12 are preferably provided with wings 13, which are bent around adjacent portions of the legs. Either or both plates may be omitted when desired.

The free ends of the gripping arms constituting each pair are provided with male and female elements 6x, 6x', respectively (see Fig. 7), and these elements are surrounded by collars 6', which engage the opposite faces of the film. By providing for the guiding of the gripping arms or their free ends toward and from each other, wear and danger of the elements 6x, 6x', being damaged are eliminated.

The weight 2 preferably consists of a lead body (which may be cast) having an oval shape in cross-section. The body 2 is formed adjacent its ends with slots 14 extending from one end of the body 2 inwardly in the direction of its major axis, the bottoms of the slots diverging downwardly relatively to said axis to insure drainage. The slots 14 are of a size and spaced to receive the loops 4 of the device 1 and after the loops 4 are set into the slots, the end portions of the outer walls of the slots are bent laterally inwardly and thus connect the weight to the loops. As the bent over walls engage the end portions of the loops 4, the resiliency of the legs 5, 5a, is not affected. The weight 2 may be positioned with the slots 14 extending up-

wardly, as shown in Fig. 1, or with the slots 14 extending downwardly, as shown in Fig. 3.

By making the weight of a rounded form, in cross-section, its exterior surfaces provide for shedding of liquid readily.

The loops 4 may be suspended from the support B or other device in any suitable manner, for example, by U-members C, which are shown removably mounted on the support, or carried by a bar D, which extends through the loops as shown in Fig. 2.

In my form of construction the loops 4 are spaced from each other and disposed in parallel relation and the pairs of gripping arms are spaced and disposed equal distances from the planes of the loops, with the result that the device may be suspended vertically from a support and the strip hung vertically from the device; also, when a weighted device is connected to the depending free end of a strip, as shown in Fig. 90 1, this arrangement and form of construction insure that the weight of the device and the weight carried thereby will tend to hold the free end of the strip down without distortional strains upon the strip. Also, it will be noted that the 100 strip is engaged at each end, or either end, by two pairs of spaced gripping members or arms, so that danger of weakening, cutting or damaging the strip is minimized and walls, corners, or recesses that may tend to hold liquid or prevent 105 free access of the drying or cooling atmosphere are materially reduced or entirely eliminated. It will also be noted that the device is made of two sections of resilient wire so arranged and constructed that the requirement for a separate 110 spring coil, to effect operation of either or both pairs of clamping members, is avoided. Furthermore, the construction and arrangement provide for unobstructed flow of liquid and air through the wire sections. As a result, very little 115 liquid can adhere to the services of the section, thus insuring economical use of the necessary chemicals and quick drying of the moisture remaining on the sections due to immersion.

It will also be noted that in my construction, 120 the legs 5, 5a, are connected by loops (which are, by preference, semi-circular loops) 4 and each leg of each pair is connected to the leg of the other pair that is on the same side of the median plane, already referred to. Accordingly, 125 it will be seen that if by accident, the device is distorted, so that the gripping elements are in dis-alinement, and cannot function, my construction and arrangement permit the legs to be readily re-bent, manually, to bring the portions 130 7, 7, and elements 6x, 6x', into operative relation, normally engaged, and ready for use.

To those skilled in the art to which my invention relates, many changes in construction and widely differing embodiments and applications of the invention will suggest themselves without departing from the spirit and scope thereof. My disclosures and the description herein are purely illustrative and are not intended to be in any sense limiting.

What I claim is:

1. An article of the class described comprising a pair of resilient wire sections bent intermediate their ends to form legs terminating in clamping members normally in engagement, the legs of one 145 section being substantially parallel to the legs of the other section, and a connection between each leg of one section and the corresponding leg of the other section, whereby each two connected legs move together.

2. An article of the class described comprising a pair of resilient wire sections bent intermediate their ends to form legs, the legs of each section terminating in clamping members normally in engagement, the legs of one section being substantially parallel to the legs of the other section, and a connection between each leg of one section and the corresponding leg of the other section, whereby each two connected legs move together. 80
- 5 3. An article of the class described comprising a pair of resilient wire sections looped intermediate their ends to form legs, the legs of each section terminating in gripping members normally in engagement, the legs of each section between said loops and gripping members being off-set toward the legs of the other section, and a connection between the off-sets of adjacent legs, whereby each two connected legs move together. 85
- 10 4. An article of the class described comprising a pair of resilient wire sections bent intermediate their ends to form legs, the end portions of the legs being bent laterally and extending beyond a median plane between the legs and reversely curved with their free ends normally engaged, and a connection between each leg of one section and the corresponding leg of the other section, whereby each two connected legs move together. 90
- 15 5. An article of the class described comprising a pair of resilient wire sections bent intermediate their ends to form legs, the end portions of the legs of each section being bent into intersecting relation and terminating in clamping members normally in engagement, and a connection between each leg of one section and the corresponding leg of the other section, whereby each two connected legs move together. 95
- 20 6. An article of the class described comprising a pair of resilient wire sections bent intermediate their ends to form legs, the end portions of the legs of each section being bent into intersecting relation and terminating in clamping members normally in engagement, said intersecting portions having sliding engagement to maintain the clamping members in alinement, and a connection between each leg of one section and the corresponding leg of the other section, whereby each two connected legs move together. 100
- 25 7. An article of the class described comprising a pair of resilient wire sections bent intermediate their ends to form legs, the end portions of the legs of each section being bent into intersecting relation and terminating in gripping members normally in engagement, a connection between each leg of one section and the corresponding adjacent leg of the other section, whereby each two connected legs move together, and a weight connected to said loops. 105
- 30 8. An article of the class described comprising a pair of resilient wire sections folded intermediate their ends to form pairs of legs, the legs of each section terminating in gripping members normally in engagement, the legs of each section between said loops and gripping members being off-set toward the legs of the other section, a connection between the off-sets of adjacent legs, whereby each two connected legs move together, and a weight connected to said loops. 110
- 35 9. An article of the class described comprising a pair of resilient wire sections folded intermediate their ends to form pairs of legs, the legs of each section terminating in gripping members normally in engagement, a connection between each leg of one section and the corresponding adjacent leg of the other section, whereby each two connected legs move together, and a weight engaging the folds of said sections. 115
- 40 10. An article of the class described comprising a pair of resilient wire sections bent intermediate their ends to form legs, the legs of each section terminating in male and female clamping members normally in engagement, and a connection between each leg of one section and the corresponding leg of the other section, whereby each two connected legs move together. 120
- 45 11. An article of the class described comprising a pair of resilient wire sections bent intermediate their ends to form legs, the legs of each section terminating in male and female clamping members normally in engagement, a collar surrounding each said member inwardly of its engaging surface arranged to engage the collar on the other opposed member, and a connection between each leg of one section and the corresponding leg of the other section, whereby each two connected legs move together. 125
- 50 55 130
- 55 60 135
- 60 65 140
- 65 70 145
- 70 75 150
